UNITED STATES PATENT OFFICE

BURT A. PETERSON, OF ROCKFORD, ILLINOIS, ASSIGNOR TO BARBER-COLMAN COMPANY,
OF ROCKFORD, ILLINOIS, A CORPORATION OF ILLINOIS

WARPING APPARATUS

Application filed June 6, 1928. Serial No. 283,244.

The object of the present invention is to expedite creel replenishment and thus reduce idle time of the warper. This object has been attained by providing a creel of such construction that it may be loaded with a new set of cheeses while the warper is running, the arrangement being such that the new set of cheeses may be quickly and conveniently placed in unwinding position. The creel is of sectional construction, each section having two duplicate series of cheese supports, one series of supports being accessible to the operator for replenishment while the cheeses on the other series of supports are being unwound.

In the accompanying drawings,

Figure 1 is a side elevation of a warping apparatus embodying the features of my invention.

Fig. 2 is a plan view thereof.

Fig. 3 is a vertical sectional view in the plane of line 3—3 of Fig. 2.

Fig. 4 is a view looking from the right-hand side of Fig. 3.

Fig. 5 is a fragmental perspective view of the creel.

Fig. 6 is a detail view of the thread guiding means.

As shown in Fig. 1, the apparatus comprises a warper A and a creel B. In the present instance, I have shown a beam warper, but it will be understood that the invention is applicable as well to a ball warper. For a disclosure of a warper in connection with which the present invention may be used, reference may be made to my application Serial No. 706,834, filed April 16, 1924, which application will mature into Patent No. 1,672,470 on June 5, 1928.

While the creel B may partake of various forms, it is herein shown as comprising two upright frames 1 and 2 which are adjacent each other at one end and separated from each other at the opposite end so as to constitute a V-shaped structure. The frames 1 and 2 are rigidly connected together at their adjacent ends by means of a frame member 3 and at their upper portions by means of cross-bars 4. Each of the frames 1 and 2 includes, in this instance, two parallel bottom frame

members 5 and 6, transverse connecting members 7, a longitudinal top member 8, end members 8^a, and a series of wooden posts 9 connecting the lower and upper frame members 5 and 8. Each of the frame members 1 and 2 further comprises a series of creel sections 10 (Fig. 3). Each creel section consists of an upright 11 rotatably suspended from a trolley or carrier 12 adapted to run within a tubular track 13 which is secured to the lower sides of the cross-bars 4 parallel with the frame members 5, 6 and 8. Projecting from the lower end of the upright 11 is a guide stud 14 that extends slidably within the space between the upper flange of the frame member 6 and a rail 15 secured to the transverse members 7. To space apart the uprights 11, each of the creel sections 10 comprises horizontal distance pieces 16 projecting from opposite sides of the uprights 11 in position to abut the distance pieces on adjacent creel sections.

While certain features of the invention are adapted for use in connection with the unwinding of yarn masses of various forms and types, I have herein shown the creel sections 10 as especially adapted to support cross-wound cylindrical yarn masses of the type commonly termed "cheeses". In the drawings the cheeses are indicated at a. Each consists of yarn spirally wound upon a tubular core b (Fig. 3). The cheese is non-rotatably mounted upon a spindle 17 rigidly secured to the upright 11. A curved leaf spring 18 secured in a groove in the periphery of the spindle 17 projects out of said groove sufficiently to engage the interior of the cheese core and exerts sufficient pressure against the core to hold the cheese against rotation and to insure that the cheese shall not be casually displaced from the spindle. Surrounding each spindle is a cylindrical casing 19 having a closed end 20 which is rigidly secured to the upright 11. The opposite end of the casing is open for the insertion of full cheeses.

As shown in Fig. 5, the spindle 17 and casings 19 are arranged in two columns, one on each side of the upright 11, the casings on a given side of the upright being in con-

tact with each other. To permit compact spacing of the cheese supports the casings 19 on one creel section are staggered with relation to the casings on the next adjacent 5 creel sections.

The spindles 17 may be considered as arranged in pairs, one spindle of each pair being accessible from the interior of the creel frame while the other spindle is in unwinding 10 position. The spindles of each pair are axially alined.

When unwinding yarn from a stationarily-mounted cross-wound yarn mass, lint collects 15 on the rear end of the yarn mass, unless prevented from so doing. Such accumulation of lint is objectionable, as it is carried off by the yarn in bunches. In a certain prior-art 20 warper, electric fans located outside the creel are employed to prevent lint from settling on the yarn masses. One of the functions of 25 the casings 19 herein disclosed is to enable the ballooning yarn to set up air currents that blow the lint out toward the front of the creel and thus prevent lint from accumulating on the yarn masses. Another function of the casing 19 is to keep the ballooning threads out of contact with one another.

When the creel sections 10 are compactly arranged in running position (as shown in 30 Fig. 1 and in the right-hand portion of Fig. 5), one column of cheese supports on each creel section faces toward the outer side of the creel, while the other column of cheese supports faces toward the inner side of the creel, thus permitting loading of the last mentioned 35 column of cheese supports while a set of cheeses is being unwound.

After filling the reserve or inner sides of 40 the creel sections, the operative collects the threads of each column, beginning at the top of the column and drawing the thread ends down to the bottom. To hold the thread ends in place until the time arrives to draw them forward to the warper, there is provided 45 a clip or holder 21 on the lowermost casing 19 (see Figs. 3, 4 and 5).

The devices for guiding the yarn in its course from the cheeses to the warper and the means for detecting exhaustion of the 50 yarn are supported upon the posts 9. On the inner side of each post is a series of yarn guides, herein shown as formed by means of a plate 23 (Figs. 3 and 6) having openings 24 each formed in axial alinement with one 55 of the cheeses being unwound. A slot 25 extends from the edge of the plate to the opening 24 to admit the yarn to the latter. On the inner side of the plate 23 is secured a yarn guide 26 which is alined with the axis 60 of the cheese. The yarn guide 26 is in the form of a curved finger, its closed side being opposite the entrance slot 25.

The operation of replenishing the creel is 65 as follows: The cheese spindles at the inner side of the creel are supplied with cheeses

while the warper is running. When the cheeses which are in operative position have been unwound to the desired extent and have been disconnected from the beam, the operator turns the creel sections 10 through 180°, 70 beginning with the creel section farthest from the warper. By reference to Figs. 1 and 2, it will be seen that each creel frame 1 and 2 is long enough to allow the creel sections to be slid successively away from the next adjoining creel section to permit of turning the creel section to place the newly loaded side thereof at the outer side of the creel. All of the creel sections having been 75 thus turned, they are pushed up toward the front end of the creel (as shown in Fig. 1), in readiness to be connected to the beam.

While the present embodiment of the invention has been described in considerable detail, it will be understood that various modifications of details and rearrangements of mechanisms may be made, within the scope 80 of the appended claims, without departing from the spirit of the invention.

I claim as my invention:

1. A V-shaped warper creel comprising two frames arranged in vertical planes that converge in the form of a V, creel sections in each of said frames, said sections being slid- 90 able longitudinally of the respective frames toward and away from the apex of the V-shaped creel, each of said creel sections comprising pairs of yarn mass supports, one sup- 95 port of each pair being accessible from one side of the frame for replenishment while the other support of the pair is in unwinding position, and said pairs of support being rotatable on an axis located between the sup- 100 ports, and yarn guiding means on the outer side of each of said frames for guiding the yarn in the general direction of said apex.

2. A warper creel comprising a frame, creel sections independently movable longitudinally of said frame and always occupying the same plane, each of said sections comprising pairs of yarn mass supports, one sup- 105 port of each pair being accessible from one side of the frame for replenishment while the other support of the pair is in unwinding position, and said pairs of supports being rotatable on an axis located between the sup- 110 ports.

3. A creel comprising a vertical series of 115 yarn mass supports, each being arranged to support a yarn mass on a horizontal axis, and a casing enclosing each support and having an open vertical side for the insertion of the yarn mass and the withdrawal of the 120 yarn, the ballooning yarn in said casings setting up air currents that blow the lint out of 125 the casings.

In testimony whereof, I have hereunto affixed my signature.

BURT A. PETERSON.
